UNITED STATES PATENT OFFICE.

BENJAMIN F. ORTON, OF NEW YORK, N. Y.

ARMATURE FOR DYNAMO-ELECTRIC MACHINES.

SPECIFICATION forming part of Letters Patent No. 308,851, dated December 2, 1884.

Application filed January 23, 1884. (No model.)

To all whom it may concern:

Be it known that I, BENJAMIN F. ORTON, a citizen of the United States, and a resident of New York, in the county of New York and State of New York, have invented certain new and useful Improvements in Armatures for Dynamo - Electric Machines or Motors, of which the following is a specification.

My invention relates to the construction of so-called "sectional armatures," in which the armature core or carrier is built up from two or more curved segments, each forming or embracing a portion only of the circumference of the armature.

The object of my invention is, first, to provide a simple and effective means for securing adjoining segments or sections together; second, to so construct the armature that the armature-coils may be wound separately in a lathe or otherwise upon a suitable bobbin or holder, and may then be slipped endwise into place upon the armature-segments and held in place by any suitable means. By such a construction I greatly facilitate the making of sectional armatures, and at the same time secure the important result that any armature coil or bobbin may be readily removed at any time, in case it becomes damaged, and its place filled by a new and perfect coil and bobbin. Moreover, there is no difficulty encountered in making the armature-core of two pieces only, each making a half of the circumference of the armature, since in my invention the armature-segments do not require to be placed in a lathe for the purpose of winding the armature-coils upon them; but said coils are wound upon their bobbins separately and then slipped into place upon the armature section or segment.

To the above ends my invention consists in certain improvements in the construction and in the combinations of parts, the nature of which will be readily understood from the accompanying description and drawings, and which will be specified in the claims.

Figure 1 shows, in elevation and partially in section, a portion of an armature constructed according to my invention. Fig. 2 is a section, at right angles to the armature-axis, of an armature having an improved device for fastening the armature segments or sections to-

gether. Fig. 3 is a cross-section on the line 6 of Fig. 1. Fig. 4 is a plan of a portion of an armature-segment spread upon the plane of the paper, and showing in plan three armature-coils in place upon the segment, as also modifications of the keying or locking device interposed between the armature-bobbins for holding them in place. Fig. 5 is a cross-section on the line 5 5 of Fig. 1.

In the drawings I have shown my present invention as applied to an armature whose core is built up and supported in the general way described and claimed in another application for patent filed by me December 11, 1883, No. 114,161. In such application I propose to build the armature-segments up from superimposed curved plates separated by washers or plates of iron, and resting at their abutting ends upon tables or plates formed upon the ends of armature-spokes or radial arms, and secured by stirrups or saddles embracing the abutting ends and extending across from one side of the armature to the other. I do not, however, wish to be understood as limiting myself to this special construction of or method of supporting and securing the individual segments, and have shown this form only for the purpose of illustration of the features to which my present invention relates.

In Fig. 1, *a a a*, &c., indicate thin curved plates of iron, each extending through half the circumference of the armature, that are secured together and to plates *A* by bolts or rivets *b b*, or other devices, and are separated by washers or blocks *c c* of iron or other material. The armature-segments thus formed rest upon the plates or tables *d d*, formed upon the ends of the spokes *e e*, and are held in place by the saddles *f f*, bolted to the sides of the plates *d d*, and extending across from one side of the armature to the other in a direction parallel to the axis of the machine.

A indicates a tray-like under plate, forming a portion of the core, and upon which the other plates, *a a*, rest.

The parts so far as described are in substance the same as in my prior case; but the sections or segments differ from those described in my prior case, as well as from those of other armatures, in that each segment is free from lateral lugs or projections for hold-

ing the armature-bobbins in place, and is made of proper size to permit the bobbins, after being wound, to be slipped into place over the end of the segment. The general 5 contour of the segment is shown in Figs. 3 and 4, and its largest portion is at $m m$, where each bobbin rests. At this portion it is supposed to fill the interior space of the bobbin, so that the latter, after being slipped into position, will be held firmly.

Between the portions $m m$ are the slots or notches $n n$, formed in each plate $a a \Delta$, and adapted to form keyways or guides for holding blocks or keys of a suitable form to fill the 15 slots and interposed between the bobbins for the purpose of locking them together and firmly in place. The keys are slipped into place sidewise or from the exterior of the armature, and are held in place by any suitable 20 device—such, for instance, as that hereinafter described. The keys are preferably of iron, and these serve also to bring the magnetism of the core into the space between the bobbins and close to the pole-pieces of the field- 25 magnet.

The bobbins or holders for the armature-coils are indicated at $h h$, and are of any suitable or desirable construction for receiving and holding the armature-coils $k k$, which are 30 wound upon the bobbins in any suitable manner previous to the placing of the same upon the armature.

In Fig. 1 five bobbins are shown in place—four filled with coils and the other empty.

35 The keys may be solid or made up, like the armature-segments, from a series of plates or strips $t t$, bolted or secured together by rivets or bolts p , Figs. 4 and 5. I prefer to make such keys of iron or of iron plates, and to 40 separate them by washers or blocks r , Fig. 5. This construction both breaks up the circulation of Foucault or induced currents and likewise helps to keep the armature cool.

The keys may be constructed separately and 45 fill the space between the bobbins on the side only of the armature, as indicated in top view at $H H$, Fig. 4; or they may be so made as to also fill the space between the bobbins on the exterior of the armature, as indicated at $L L$, 50 Fig. 4, and in cross-section in Fig. 5, where the additional portion filling such space is shown made up of thin plates separated by washers and secured together and to the plates filling the side spaces by a bolt. With such construction it is obvious that the key must be 55 slipped into position from the outer side of the armature. The keys are held in position against centrifugal action by cap-plates s , of any desired form, which bridge the two arms 60 of a stirrup, t^2 , opening upward and extending across on the inner side of the armature. The plates s are secured to the stirrups by nuts s^2 upon screw-threaded studs at the ends of the stirrup-arms, as shown.

65 Instead of making the keys in the form before described, they may be made in other

forms—as, for instance, in the form shown at B^2 , Fig. 4, where the base of the key, or that portion next the armature-core, has transverse teeth or webs extending outward at right angles from the core to a point flush with or nearly flush with the outer surface of the coils.

To prevent endwise movement of the segments in their bearings or tables d , I cut the plates $a A$ with an offset or rabbet, (indicated 70 at w , Fig. 4,) which rests against the edges of the supports d and the saddles f .

A preferred device for securing the ends of the core-segments together is shown in Fig. 2. It consists of the L or angle pieces $H^2 H^2$, having their radial portion secured together by a bolt or bolts, M , while their circumferential portions are bolted, respectively, to the abutting ends of the armature-segments or are otherwise secured to them. The L -pieces are 85 preferably of iron, and by abutting closely against one another help to maintain the magnetic continuity of the core.

In applying and securing the armature-bobbins in place, they are, after being wound, 90 slipped separately over the end of the armature-segment.

After putting a bobbin in place, keys are applied and secured next to it by the stirrups t^2 and plates s , and other bobbins and keys 95 are then placed alternately upon the armature-segment in obvious manner. If at any time it be desirable to remove a bobbin, it is easy to do so by removing the keys and slipping the bobbins off from the end of the segment until the defective bobbin is reached.

I do not limit myself as to the construction of the armature-core, nor to any particular device for holding the keys in place.

Other modifications coming under the invention claimed will readily occur to those skilled in the art.

What I claim as my invention is—

1. The combination, with an armature-core made up of core-sections free from projections 110 and of proper size to permit the armature-bobbins to be slipped into place endwise upon it, of a carrier or supporting frame, upon which abutting ends of the core-sections rest, and clamping devices whereby the core-sections 115 may be held together at their abutting ends, where they rest on the frame.

2. The combination, with the armature-segment having notches or recesses at its sides, of the key-pieces in said notches and between 120 the armature-bobbins, as and for the purpose described.

3. The combination, with the armature-bobbins, of the interposed attached key-pieces made up of superposed metal plates, as and 125 for the purpose described.

4. The combination, with the armature-segments having slots or recesses in their sides, of the key-pieces, as and for the purpose described.

5. An armature segment or section made up 130 of superimposed plates curved to the form of

the armature-ring or cylinder, and having notches or recesses in their edges, in combination with key-pieces fitting said notches, as and for the purpose described.

5 6. The combination, with two segments or sections in a sectional armature, of two L-pieces bolted to one another and individually bolted to the abutting ends of the segments, as and for the purpose described.

7. The combination, with the armature and

its bobbins, of the removable keys and the stirrups and cross-plates for holding the keys in place.

Signed at New York, in the county of New York and State of New York, this 21st day of 15 January, A. D. 1884.

BENJAMIN F. ORTON.
